UNITED STATES PATENT OFFICE

FÉLIX LÓPEZ-OSORIO, OF BUENOS AIRES, ARGENTINA

TRANSFORMABLE MOTOR-CAR BODY

Application filed September 28, 1928. Serial No. 308,973.

This invention relates to a convertible type of car body having an unusually long chassis and being further provided with cut-in rear doors to accommodate the rear fenders, and has particular reference to the construction and arrangement of a collapsible roof and side wall frame which, in any of its positions, open or closed, will give no intimation that the car is convertible.

10 This invention is a further development of an invention described in Letters Patent No. 1,772,672 issued to me on August 12, 1930.

The invention has for its object to provide a convertible vehicle body of the character hereinafter described, which includes a collapsible frame capable of folding into a pocket in the body below the side door openings, which pocket is limited in its length to 20 a dimension considerably shorter than the required overall length of the frame when in its up position to support a full length top.

I accomplish this object by means of an arrangement which consists briefly in a car body having its rear doors cut away to accommodate the curve of the rear mudguards and the storage space between the front and rear mudguards, as a consequence, is insufficient to accommodate the longitudinal beams of the roof. It is therefore, contemplated to construct the longitudinal beams of the roof in the manner of a telescope, so that the same may be collapsed to a dimension which can be accommodated by the 35 available storage space.

One embodiment of the invention is illustratively exemplified in the accompanying drawings, in which, Figure 1 is a side elevational view of a car having a convertible body showing the top erected; Figure 2 is a perspective view of one side of the body showing the rear door opening and the longitudinal beam in folded position and arranged in the storage space beneath the door opening and between the mudguards; and Figure 3 is a perspective view of the longitudinal beam in its extended position.

Referring to the drawings, 10 denotes a car body of the double phaeton type in

which the rear mudguards 11 cut into the corner of the rear door opening 12, the front mudguard 13 being provided at its lower end adjacent the running board 14, with a pocket for the purpose hereinafter described. The 55 rear wall 15 of the body beyond the rear opening 12 is divided to accommodate the upright rear arm 4 of a U-shaped longitudinal beam called a swing 5. The free end of the arm 4 is provided with a pin 3 which 60 projects at right angles to the arm in a rearward direction and into an opening 16 in the rear wall 15, as illustrated in Figure 2. In closed position, i. e. the top being down, the arm 4 hangs downwardly from pin 3 65 and is accommodated in a cutout 17 in the floor board 18, and at its lower end below the board 18, the arm 4 is provided with a pin 19 projecting at right angles thereto and extending into an opening 20 in the end of 70 the cross beam of the swing 5. The door 21 is supported on hinges 22 and swings over the outside of the arm 4, which as previously described, is accommodated in the space between the sides of the rear wall 15. 75

To erect the top, the swing is turned on the pin 3 to bring the beam 5 above the body, whereupon the arm 4 is extended towards the rear until the beam 5 covers the distance between *a* and *b*, see Figure 1. The covering is stretched in position between *c* and *b*, the area between *c* and *a* being unsupported except at the ends 6 of the swing and the upper corners of the windshield frame 23. 80

To provide more space than exists between the two mudguards 11 and 13, the front guard 13 is provided with a pocket 24, which forms the terminal for the front end of the box or storage space 1, arranged beneath the door openings to accommodate the folded flexible 90 covering when the frame is lowered.

Having now described my invention, what I claim and desire to secure by Letters Patent, is:

1. In a convertible automobile body comprising a side wall having an opening therein and a floor board provided with an opening, the combination therewith of a roof supporting device comprising an extensible and contractible beam designed to be moved into 95

and out of the opening in the floor board and a supporting frame for said beam having a member movably mounted in the opening in the side wall, whereby said beam may be 5 swung upwardly into roof supporting position or downwardly out of such position.

2. In a convertible automobile body comprising a side wall having an opening therein and a floor board provided with an opening, 10 the combination therewith of a roof supporting device comprising a beam designed to be moved into and out of the opening in the floor board and a supporting frame for said beam, said supporting frame comprising a member telescopically corelated to one end of said beam, a second member movably supported 15 in the opening in the side wall and a third member connecting said two frame members to each other, whereby said beam may be 20 swung upwardly into roof supporting position or downwardly out of such position.

FÉLIX LÓPEZ-OSORIO.
